DOOR MOUNTING

Filed Dec. 11, 1924

FIG. I

FIG. 2

FIG. 3

FIG. 6

INVENTOR.

EDWARD J. DEISLEY

113

BY ATTORNEY.

ATTORNEY.

UNITED STATES PATENT OFFICE.

EDWARD J. DEISLEY, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA.

DOOR MOUNTING.

Application filed December 11, 1924. Serial No. 755,148.

The door mounting of my invention is of a special adaptation in the art of pressed metal vehicle body construction. The invention is a result of the endeavor to improve the range of vision from within closed body vehicles of this construction. While of this particular inception and adaptation, however, it possesses much general merit as a door mounting per se and will probably be found of considerable utility in other portions of the field to which it belongs.

Recently, very marked improvement in the range of vision from the interior of closed body vehicles of pressed metal construction has been made through inventions of improved door locks which permitted the windows to be made the full width of the door between the side rails, by improved constructions of the door posts and door frames and in still other ways. This invention marks a still further advance and also a marked improvement in the same line. Whereas the foregoing improvements permitted full width windows between the rails of the door, they did not permit the employment of the thinnest possible rail section in the case of the mounting rail of the door, which rail takes the door hinges through which the door is mounted upon the door post. Certain of the locks which have been invented in this general trend of the art have permitted use of the very thinnest sections in the case of the jamb rail of the door. The present invention permits use of equally thin section in the case of the mounting rail.

In the main, my invention consists in securing the hinge in such manner that its body is entirely exterior to the body of the mounting rail. I am able to do this by providing an inward offset in the adjacent face of the mounting door post of sufficient depth to accommodate the projecting body of that wing of the hinge secured to the mounting rail, by accommodating the body of the complementary wing within the body of the mounting door post preferably adjacent to said offset, and by effectively bracing and securing said hinge wings in place. My invention includes very novel means of attaining these several ends. It is in these means that my invention will probably find its greatest utility in other portions of the field

because through them the door mounting is not only made very adaptable, but more compact, of greater strength and of an inherent simplicity which insures a lowered cost of manufacture and installation.

In the accompanying drawings, I show a good embodiment of my invention, an embodiment in a pressed metal construction. I have found it to possess the advantages set forth in an especially high degree.

Of the drawings,

Fig. 1 is a side elevation of a closed automobile body of pressed metal construction.

Fig. 2 is a horizontal section of one of the several door mountings of this embodiment which are contained by the body shown in Fig. 1, which horizontal section is taken substantially on lines 2—2 on Fig. 1.

Fig. 3 is a vertical, sectional elevation taken on line 3—3 of Fig. 2.

Fig. 4 is also a vertical, sectional elevation but in this case taken on a line 4—4 at right angles to the line 3—3 of Fig. 2.

Fig. 5 is an entirely similar section taken on line 5—5, looking in the opposite direction as shown by its arrows.

Fig. 6 is a side elevation of a re-inforcing part and

Fig. 7 is a transverse section of the same on lines 7—7 of Fig. 6.

The closed body illustrated is of the Sedan type. It is provided with two doors 10 and 11 which are shown as closing toward each other against an intermediate door post. These doors are comprised of jamb rails 12 and mounting rails 13 constituting the sides of the door frame. Hinges 14 connect the mounting rails 13 with door posts 15. In the upper portion of each door is a window 16, usually of plate glass. My invention is comprehended in the construction and inter-relation between the mounting rail 13, the windows 16, the hinges 14 and the door mounting posts 15. Its salient features are shown in the detail of Figs. 2 to 7 inclusive, as applied particularly to the structure associated with the front lower hinge, but it should be understood that in the main these same features of construction apply to corresponding portions of the mountings associated with each of the hinges 14 throughout the body of the car.

Referring now to Figs. 2 to 7, it will be

seen that the door mounting post is designated as 15, the hinge as 14, the mounting rail as 13 and the window as 16, just as in Fig. 1. The door rail 13 is of Z-section comprising a body web 17, an outer overlapping flange 18, adapted to close neatly and effectively the crack between the mounting rail 13 and the door post 15, and an inner arm or flange 19, adapted to receive other parts of the door structure as, for example, the lock plate and upholstery. The body web 17 of this rail is of the very thinnest section, compatible with strength. Secured flatly against it is a glass run channel 20 comprised of a pair of angle members appropriately welded to the inner face thereof. The glass of window 16 is confined in this channel and extends, therefore, substantially all the way over against the thin web 17 of the mounting rail 13 itself.

The hinge comprises two wings, one, 21, secured flatly against the outer face of the web 17 of mounting rail 13 and having its body projecting substantially wholly from this outer face. The other wing 22 is accommodated within the body of the door post 15.

The door mounting post 15 is of channel or other hollow construction, its mounting face is inwardly offset, at 23, as most clearly appears in Fig. 3. The projecting body of the wing 21, when the door is closed, is accommodated in part at least within this offset. The wing 22 is secured in this embodiment flatly against the inner face of the mounting wall at this inward offset. The wing 22 passes into the body of door post 15 through a socketing aperture 24. This socket is supplemented by a socket 25 formed by a bridging member 26. This bridging member extends across the end of wing 22 from a point below to a point above and its opposite ends are respectively secured to the inner walls of the post 15 by any suitable means. Preferably the bridging member is in the form of a pressed metal stamping, the body of which is deflected laterally to form the snug socket shown particularly in Fig. 3 and the ends of which are electrically spot welded to the wall of the post. The hinge wing 22 is secured within the socket by machine screws 27 applied from the mounting face and passing commonly through the mounting wall of the post, the body of the hinge wing 22 and the body of the bridging member 26. The heads of these screws are counter-sunk to make a flush face on the inward offset and when screwed home they secure these several parts firmly together. By removing them and withdrawing the wing 22 from sockets 24 and 25, the door may be demounted.

The bridging member 26 is provided with a laterally extending offset from its inner edge extending toward the opposite wall of

post 15 from the inward offset 23. Interconnecting this projection 28 and the inner flange 19 of the mounting rail 13, or other part of the door frame, is a door check strap 29 secured in place by clips 30 at its opposite ends screwed or otherwise secured to the respective members of attachment, 28 and 19. The projection, 28, in turn, is guyed by a strap 31 (Fig. 1 and Fig. 2) to a portion of the body lying to one side of the door to which the mounting is applied. As shown in the two illustrated instances in Fig. 1, in the one case the guy extends to the cowl structure, and in the other to the wheel housing structure of the body. This functions to take the severe strains of the door check and to prevent spreading of the channel section of the door post 15 and other tendencies to displace the post and the mounting as a whole, the tendencies to weaken the mounting. Preferably, this guy 31 is applied to the projection 28 by spot welding. The door check is applied by a screw or screws which pass through both pieces. In fact, the guy is a bridge between the hinge mounting wall of the door post and the opposite wall and it may, if desired, be connected directly to the opposite wall rather than indirectly through extension to the structure at a point beyond the same.

I do not claim as my invention the broad construction of a lateral brace applied to one side wall of a pressed metal post at the point of connection to it of the door check or of the hinge, as that matter is described and claimed in a copending application, Ser. No. 741,262, filed Oct. 2, 1924, by Joseph Ledwinka for pressed metal body construction. I do claim this construction in combination with my improved hinge mounting including a member bridging or embracing the hinge wing secured to the posts.

The hinge wing 21 which I secure to the mounting rail of the door, I rivet in place to the face of the rail. I may also weld it in place. Thus, this wing is permanently secured. It is not needful ordinarily to remove it since removability has been provided for in the complementary wing as just set forth, but it can be chiselled off. I provide lateral buttresses 32 against its edges to effectually align it during application and to reinforce the rivets in holding it against lateral displacement under strains. These buttressing devices are preferably in the form of pressed metal stampings in the shape shown in Figs. 6 and 7 of angle section, spot welded in place against the flat outer face of the thin web 17 of the mounting rail. In assembly, these stampings are welded on first. They then align the hinge wing when it is put in place.

The wing 21 further inter-sects the overlapping flange 18 of the mounting rail or door, and the body of this flange at the

line of juncture of the hinge wing 21 with the mounting rail is deflected laterally as shown at 33 in Figs. 4 and 5, to lie flatly against the inner face of wing 21. This displacement may be a bodily displacement without cutting of the flange but in the form shown is accomplished by cutting the flange at 34 on each side of the wing 21 as clearly appears in Fig. 4 whereby the displaced portion 33 assumes the form of a tab. The buttressing stampings 32 are provided with projections 35 in the form of square heads in extension of the buttressing branch of the angle section (Fig. 6), and these projections lie within and substantially fill up the cuts 34 by means of which the portion 33 of the overlap flange has been displaced.

The displaced portion 33 of the overlapping flange 18 and these projections 35 together with a body of metal 36 applied by gas welding or equivalent means, constitutes a fillet structure encompassing the inner face and the edges of the hinge at this line of meeting with the door or the mounting rail. 13. The body of metal 36 welds the projections 32 and the flange portion 33 strongly together and to the panel of the door, but is not welded to the hinge wing. Thus is formed a finishing fillet which most strongly reinforces the wing securement as a whole, and furthers the effectiveness of the door mounting at large.

A projection 37 from wing 21 lying in the plane of the flange 18 and extending across its width and into contiguity with wing 22, not only serves as a stop and spacer between the hinge wings, but also effectually closes the gap between them and thereby eliminates drafts and attains a neat appearance.

The inherent simplicity, the small number of parts, the ruggedness of the construction and connections and the firm bracing can now be clearly appreciated. Yet, I have sacrificed no essential requirement of a door mounting. Ease of assembly and facility in demounting are each provided for, yet neatness of appearance and fineness of finish have been retained. Above all, a door rail of the very thinnest section is used and the transparent window is carried all the way over to the web of this thin section, reducing to a minimum the opaque projection offered by the door mounting rail from within the car. The range of vision through the door window is thereby markedly amplified. Still further, the ruggedness of construction and structural features thereof enable me to reduce the combined section of the parts entering into the mounting at large, to wit, those parts shown particularly in Fig. 2 and thereby to enhance the range of vision not only through the door window but through other windows, as, for example, the front window or wind-

shield, or any other adjoining window as well. Vision from the body as a whole is improved.

The attached claims are intended to cover not only the embodiment shown but all those other embodiments of which my invention is susceptible without departing from its generic spirit.

What I claim is:

1. A pressed metal door mounting comprising a post having a mounting face provided with an inward offset, a door having a metal mounting rail of simple web section having a plane inner face and a glass run mounted directly on the plane face of said web section, and a hinge interconnecting the post and said mounting rail having one wing secured to the post at said offset and the other wing secured to the exterior face of the web of said mounting rail and entering said offset when the door is closed. 75

2. A pressed metal door mounting comprising a post of hollow form having a mounting wall provided with an inward offset, a door having a mounting rail, and a hinge interconnecting said post and said mounting rail having one wing projected inwardly of said post and secured to the inner face of said offset, and the other wing secured to said mounting rail and projecting laterally thereof toward the post and into the offset thereof when the door is closed. 90

3. A pressed metal door mounting comprising a hollow post having a mounting wall, a door having a mounting rail, a hinge having one wing connected with the mounting rail and the other wing projected inwardly of the hollow post and lying against the inner face of the wall thereof, a bridge 100 piece connected with the mounting wall and forming a socket over the inner end of the hinge wing, and means securing the wing in the socket. 105

4. A pressed metal door mounting comprising a hollow post, having a mounting wall, a door having a mounting rail, a hinge having one wing connected with the mounting rail and the other wing projected inwardly of the hollow post and lying against the inner face of the mounting wall thereof, a bridge piece connected with the wall and forming a socket over the inner end of the hinge wing, and a guy connected with 115 said bridge piece. 120

5. A door mounting comprising a door post, a door having a mounting rail, a hinge interconnecting said post and rail and having wings respectively connected to said parts, a member embracing that hinge wing which is secured to the post, a door check interconnecting said post and rail and a guy member connected to an extension of said hinge embracing member. 125

6. A pressed metal door mounting com- 130

- prising a door post, and a door mounting rail having a web section having a plane inner face against which is secured a window glass run, a door hinge having elements respectively interconnecting said post and mounting rail, the body of that element connected with the mounting rail being located on the outer face thereof, means secured to the outer face of said mounting rail laterally of said wing to prevent lateral movement thereof, and a projection integral with said means serving as part of a fillet structure at the line of meeting between said hinge wing and said mounting rail.
15. 7. A door mounting comprising a door mounting rail having a door overlap flange associated therewith, a mounting hinge wing connected with said rail and intersecting said flange, and a fillet structure at the line of juncture of said hinge wing and said mounting rail comprised in part by a deflected portion of said flange.
20. 8. A door mounting comprising a door mounting rail having a door overlap flange associated therewith, a hinge having a wing connected with said rail through a displacement of the body of said flange, edge buttressing means for said hinge wing having lateral projections, and a fillet structure at the line of juncture of said hinge wing and said flange, comprised partly by said projections from said buttressing means and partly by the displacement of said flange.
25. 9. A door mounting comprising a mount-
- ing rail, a hinge having a wing connected 35 with said rail, edge buttressing means connected with said rail and bearing laterally upon an edge of said hinge and having a projection overlying the body of said hinge wing beyond said mounting rail and welded thereto.
10. A door mounting comprising a mounting rail, a hinge wing secured to said rail, and a door overlap flange intersected by said projecting hinge and having its body 45 deflected laterally at the line of juncture between the overlap flange and mounting rail and lying against the deflecting face of said hinge rail.
11. A door mounting comprising a door 50 post, a door having an overlap flange closing the crack between the door and the post, a hinge projected through said flange and comprising wings spaced apart, and a projection from one wing in the plane of the 55 overlap closing the gap between the wings when the door is closed.
12. In a pressed metal door, a pressed metal hinge rail of single thickness, a hinge element secured to the outer face of said rail, and a pair of projections independent of the securing means on said rail embracing said hinge element for preventing lateral movement thereof.

In testimony whereof I hereunto affix my 65 signature.

EDWARD J. DEISLEY.
